UNITED STATES PATENT OFFICE.

ANNIE GLENISTER, OF EPSOM, ENGLAND.

SPRING ROLLER FOR BLINDS AND SCREENS.

Application filed June 1, 1925, Serial No. 34,141, and in Great Britain October 28, 1924.

This invention relates to spring rollers more particularly applicable to window blinds or screens and has for its object to provide an improved construction of spring roller on which is adapted to be rolled a screen or the like, of which the free end is adapted to be attached to a sliding sash so that when the sash is opened and closed the screen is unwound or wound up, whereby 5 the opening exposed by the opening of the sash will be covered by the screen. The invention also has for its object to provide an improved form of catch whereby the spring of the spring roller is maintained 10 tensioned whilst the spring roller is being placed in position in its brackets.

According to the present invention the spindle of a spring roller blind is provided with a catch adapted to pivot in a plane parallel to the spindle, the catch cooperating 20 with one or more stops or projections inside a sleeve or socket secured to one end of the roller in such a manner that when the roller is tilted from its horizontal position, 25 the catch is automatically brought into engagement with one or other of the stops or projections, whilst when the roller is returned to its horizontal position and the blind or screen slightly unwound the catch 30 is disengaged from the stop by gravity. The projecting end of the spindle is preferably hook-shaped and engages with a slot in a plate secured to the window frame, the object of this arrangement being that the 35 roller must be moved into an inclined position when being placed in position or when being removed thus ensuring the engagement of the catch with the projection to prevent the spring from unwinding.

40 The invention will now be described with reference to the accompanying drawings wherein:

Fig. 1 shows a longitudinal section of a spring roller constructed according to the 45 invention;

Fig. 2 shows a sectional plan of Fig. 1;

Fig. 3 shows in front elevation the supporting plate for the left hand end of the 50 spring roller;

Fig. 4 shows a side elevation of Fig. 3;

Fig. 5 shows a front elevation of the supporting plate for the left hand end of the 55 spring roller;

Fig. 6 shows a side elevation of Fig. 5;

Fig. 7 is a section on the line 7-7 of Fig. 1;

Fig. 8 shows the invention applied to a sash window.

The roller *a* is recessed in the usual manner to accommodate a central spindle *b* 60 around which is coiled a spring *c* one end of the spring being attached to the spindle at *d* whilst the other end of the spring is attached at *e* to projections *f* on a disc *g* secured to a sleeve or socket *l*. The spindle *b* passes through a central hole in the disc *g* and is prevented from longitudinal movement by pins *p*. The projecting end *h* of the spindle is in the form of a flat hook and has pivoted thereto a catch *j* which is adapted 70 to engage with one or more internal projections or stops *k* in the sleeve or socket *l* secured to the end of the roller *a*, which is suitably recessed for this purpose as shown. The spindle *b* may be suitably recessed as 75 indicated at *m* so that the catch *j* may pivot over a flat portion thereof and in order to provide stops for limiting the pivoting movement of the catch. The projecting end of the spindle may be provided with a hole *o* 80 at *m'* for the reception of a nail or suitable tool for the purpose of rotating the spindle for winding up the spring before the roller is placed in position. The bracket or plate *n* to receive the projecting end *h* of the spindle is provided with a slot at *o*, the slot being of a length corresponding with the depth of hooked end *h* and so arranged that normally the catch *j* will hang vertically downwards. The pivot *q* of the spring roller 90 is adapted to engage with a slot *w* in a bracket *t*. The brackets *n* and *t* are secured in position by means of pointed tags *r*, adapted to be driven into the top of a window frame, and by a suitable securing member, such as a nail or screw, passing through the hole *u* and driven into the side of the window frame. In order to hold the brackets at the required distance from the sides of the window frame, they are provided 95 with flanges *v*.

When placing the roller *a* in position the spring *c* is first tensioned by turning the spindle *b*, whereupon the roller *a* is slightly tilted from the horizontal position so as to bring the catch *j* into engagement with the stop or projection *k* (as shown in dotted lines in Fig. 1) and the spindle *b* is then slightly released so as to produce the locking action. With the roller held in the tilted position, the hooked end *h* is fitted 110 into the slot *o*, whereupon the roller is raised

to a horizontal position and the pivot *q* at its other end fitted into the slot *w* of the bracket *t*. The screen or blind *x* is then slightly unwound and the catch *f* falls by 5 gravity into a vertical position in which it is disengaged from the stop *k* (full line position Fig. 1). If the free end of the blind or screen *x* is attached to a sliding window sash *y* (Fig. 8) it will thus be seen that as 10 the sash is raised or lowered the blind is unwound or rolled up in accordance with the movement of the sash.

In order to remove the blind *x* the pivot *q* is removed from its bracket and the roller *a* 15 must be tilted in order to remove the hook *h* from the slot *o*. This tilting movement causes the catch *j* to engage automatically with one or other of the stops *k* and thus prevents the spring from being unwound.

20 The invention as above described is more particularly applicable for screens to be applied to windows so as to prevent flies and other insects or dust from entering when the window is open, but it may also be used for 25 other purposes such as for blinds for drawing over windows.

With the arrangement as above described it is possible to fit the end of the of the roller with the locking device firstly into its bracket 30 and then to fit the other end of the roller into the second bracket.

Having thus described my invention, what I claim as new and desire to secure by Letters Patent is:—

35 1. A spring roller for blinds and screens comprising a roller having a recess at one end, a pin at the other end of said roller, a sleeve secured to the recessed end of said roller and forming an extension of said roller, a bearing plate fixedly secured inside said sleeve, a spindle revolvably mounted in said bearing plate and in the recessed end of said roller, a spring coiled around said spindle, one end of said spring being secured to the 40 spindle whilst the other end thereof is secured to the bearing plate, pins passing through said spindle and being arranged on opposite sides of said bearing plate so as to prevent axial movement of said spindle, inwardly directed stops secured to said sleeve, a catch pivotally mounted on said spindle, said catch being adapted to pivot in a plane 45 parallel to the longitudinal axis of said spindle, the cooperation between the catch and the stops being such that when the roller is moved from a horizontal into an inclined position the 50 catch falls by gravity into engagement with one of the stops and remains in engagement therewith even after the roller has been returned to a horizontal position, but when the blind is slightly unwound the said catch falls by gravity into a position in which it is disengaged from the stop, a hook shaped extension formed at the free end of said spindle, and a slotted plate, the slot in said 55 plate being adapted to receive the hook shaped extension, said slot being of such a size that the hook shaped extension can only be engaged and disengaged from the said slot when the roller is in an inclined position, thus ensuring the catch being brought into 60 engagement with one of the said stops.

but when the blind is slightly unwound the said catch falls by gravity into a position in which it is disengaged from the stop, a hook shaped extension formed at the free end of said spindle, and a slotted plate, the slot in 65 said plate being adapted to receive the hook shaped extension, said slot being of such a size that the hook shaped extension can only be engaged and disengaged from the said slot when the roller is in an inclined position, thus ensuring the catch being brought into 70 engagement with one of the said stops.

2. A spring roller for blinds and screens comprising a roller having a recess at one end, a pin at the other end of said roller, a sleeve secured to the recessed end of said roller and forming an extension of said roller, a bearing plate fixedly secured inside said sleeve, a spindle revolvably mounted in said bearing plate and in the recessed end of said roller, a spring coiled around said spindle, one end of said spring being secured to the spindle whilst the other end thereof is secured to the bearing plate, pins passing through said spindle and being arranged on opposite sides of said bearing plate so as to prevent axial movement of said spindle, inwardly directed stops secured to said sleeve, said spindle having a recessed portion extending substantially to the longitudinal axis of said spindle, a catch pivotally mounted in said recessed portion and adapted to be accommodated therein, the recessed portion being of such a length so as to limit the pivoting movement of said catch, said catch being adapted to pivot in a plane parallel to the longitudinal axis of said spindle, the cooperation between the catch and the stops being such that when the roller is moved from a horizontal into an inclined position the 100 catch falls by gravity into engagement with one of the stops and remains in engagement therewith even after the roller has been returned to a horizontal position, but when the blind is slightly unwound the said catch falls by gravity into a position in which it is disengaged from the stop, a hook shaped extension formed at the free end of said spindle, and a slotted plate, the slot in said 105 plate being adapted to receive the hook shaped extension, said slot being of such a size that the hook shaped extension can only be engaged and disengaged from the said slot when the roller is in an inclined position, thus ensuring the catch being brought into 110 engagement with one of the said stops.

In witness whereof I hereunto subscribe my name this 20th day of May, 1925.

ANNIE GLENISTER.
